UNITED STATES PATENT OFFICE

HENRY C. RIEGE, OF KANSAS CITY, MISSOURI

PLASTERER'S COLLAPSIBLE HAWK

Application filed September 20, 1928. Serial No. 307,161.

The present invention relates to improvements in plasterer's hawks and the same pertains more particularly to a hawk capable of being collapsed for confining the same within 5 the limited compass of a tool box.

The prime object of the invention is to provide a hawk for use by plasterers capable of being easily divided into several sections, whereby the same may be easily disposed 10 within a tool box.

Still another object of the invention is to provide a hawk of this character wherein the sections thereof may be securely fastened together during the use of the same.

15 A further object resides in the means whereby the parts may be readily assembled or disassembled as the same may be.

After reading the following specification and claims, other important objects and 20 advantages of this invention will become apparent.

In the drawings:

Figure 1 represents a side elevation of the improved hawk.

25 Figure 2 is a top plan view of the tool,

Figure 3 is a transverse sectional view of the device.

Referring to the drawings more in detail, wherein like numerals designate like parts, 30 the material supporting plate generally referred to by numeral 1 includes a pair of plates 2 and 3 respectively. Each of the plates 2 and 3 is provided with a depending apertured lug 4, through which a protuberance 5 extending from the complementary section is adapted to project for maintaining the section in substantially co-planar relation. The abutting edge portions of the sections 2 and 3 respectively are provided with a 35 pair of spaced depending members 6-6 having registering openings therein.

A handle 7 is flared at its upper end portion 8 and in this flared end portion a recess 9 is formed. The recess 9 is adapted to receive 45 the depending members 6-6 of the plate sections 2 and 3 respectively.

An elongated stem 10 is provided with a T-head 11, while its opposite end portion is threaded to receive a nut 12.

50 In assembling this improved hawk, the T-

head is engaged into the openings of the depending members 6-6, in the manner clearly shown in Figure 3 of the drawings. The stem portion 10 is then disposed through the longitudinal bore of the handle 7 and the projecting threaded end portion thereof is equipped with a nut 12, whereby the threading thereof against the adjacent end of the handle will result in the tight binding of the plate section against the opposite end of the handle. 55

For the purpose of preventing the plate section from rotating the handle, teats 13 on the flared end of the handle engage within recesses on the bottom side of the plate section in the manner shown in Figure 3. 60

It is to be understood that this improved implement may be manufactured of any material, and that certain changes in the size and shape thereof may be resorted to, without departing from the spirit of the invention or 70 the scope of the appended claims.

Having thus described the invention, what is claimed as new is:

1. In a plasterer's hawk comprising a material supporting plate constructed of a pair 75 of abutting sections, a handle formed with a recess at its upper end, said sections provided adjacent their abutting edges with depending apertured lugs, said lugs being adapted to engage within the recess of the handle, and 80 means engageable within the apertures of the lugs for detachably securing the plates together and to the handle.

2. A plasterer's hawk comprising a sectional plate for supporting plaster, said sections being disposed in abutting relation, depending ears adjacent the abutting edges of the sections, a handle and adjustable means connecting the ears to the handle. 85

In testimony whereof I affix my signature. 90

HENRY C. RIEGE.
